UNITED STATES PATENT OFFICE

JOHN O. GROSS, OF LITTLETON, COLORADO

CABINET INCUBATOR

Application filed December 7, 1929. Serial No. 412,460.

This invention relates to incubators designed for hatching out eggs and one of the objects of this invention is to provide an incubator in which the air is moved in a circle transverse to the length of the incubator by a rotary fan extending practically the full length of the incubator.

A further object in this connection is to so dispose the fan that it is out of the way and in such position that there is no danger of an attendant being struck by the fan upon opening the doors of the incubator.

A further object in this connection is to provide means for securing a proper circulation of the air which will not be in the nature of a forced draft nor a mere stirring up of the air, but in which the air will be given a circular movement, bringing the entire volume of air contained in the incubator into motion, thus leaving no pockets or corners of dead air.

A further object is to divide the incubator into units and provide each unit with a heater, preferably an electrical heater, these heaters being controlled independently for each unit so that each unit has its own separate heating means and preferably an automatic regulator therefor.

Another object is to divide the incubator into units as they may be termed, each unit having a rack adapted to contain a plurality of trays and the racks being either independently or unitarily oscillatable so that the racks may be tilted to an angle of 45° each way by a lever at the rear of the machine.

Another object is to provide means whereby the trays may be inserted into the racks from the front of the incubator, the trays being mounted for movement on axes extending transversely of the length of the incubator but parallel to the movement of the air and the racks being so constructed as not to require that the trays be fastened in the racks before the racks are turned or tilted.

Another object is to provide an incubator having a special heating compartment with racks for hatching trays, which section may be operated only during the heating time or for three days per week, thus effecting a

saving during the balance of the week of four days.

Other objects will appear in the course of the following description.

My invention is illustrated in the accompanying drawings, wherein:—

Figure 1 is a longitudinal sectional view through an incubator constructed in accordance with my invention;

Figure 2 is a section on the line 2—2 of Figure 1;

Figure 3 is a section on the line 3—3 of Figure 1.

Referring to these drawings, 10 designates the outer casing of the incubator which may be formed upon its rear and front with doors whereby access may be had to the interior of the incubator. Extending longitudinally of the incubator from end to end thereof is a fan shaft 11 having thereon the fan blades 12. This fan shaft rotates in a counter-clockwise direction in Figure 2 in order to cause a circulation of air upward at the back of the incubator forward over the egg trays, downward at the front of the incubator and then again rearward and may be operated by any suitable means, as for instance, an electric motor, not shown.

Preferably the fan shaft will be rotated at a relatively slow speed so as to secure a gentle rotatory movement of the air, as shown by the arrows in Figure 2. An angular baffle 13 extends longitudinally of the casing just above the fan and just in front of the rotary axis of the fan so that the air will travel in a circle, as shown in Figure 3.

Extending transversely through the incubator from front to rear and supported in any suitable frame 14 are the shafts 15 shown as three in number, each shaft carrying upon it an egg tray rack, designated generally 16. Each rack is rectangular in form and each rack is provided with the parallel cleats 17 upon its sides forming guides into which egg trays 18 may be inserted. The rear end of each of these shafts 15 is adapted to be engaged with a crank or like means whereby the shaft may be rotated to tilt the rack from a horizontal position to a position of 45° or a small handle may be mounted

ed upon each shaft whereby the shaft may be so tilted and means may be provided for limiting the movement of this handle.

It will be seen that I have provided three of these racks 15 and beneath each rack, there is preferably disposed a heater 19 which is preferably an electrical heater having a thermostatic control. This heater is only shown diagrammatically as any suitable electric heater may be used.

Partitions may be provided between the racks 16 to thus separate the incubator in compartments one for each rack. Under these circumstances, each compartment will

have its fan 12, its own heater 19 and its own water pan 20 for the purpose of humidifying the air within the compartment. Where the compartments are open to each other, one water pan may be provided for all the compartments, but preferably there will be as many heaters as there are incubating tray racks.

I have illustrated three tray racks 16 and beyond these three tray racks, a compartment 21 is provided which may be entirely separated from the remainder of the incubator or not as desired, this compartment being provided with racks 22 for containing hatching trays 23, these racks being fixed so that the trays are held in a horizontal position.

In the use of this incubator, each setting of eggs is placed in its own special compartment or rack under its own regulator and not mixed with all ages of eggs, as is the case with other cabinet incubators. Three incubating sections permits of a setting each week, which will, of course, bring off a hatch each week. The hatching section of compartment 21 is not to be operated except during hatching time or three days per week, thus effecting a saving during the balance of the week of four days.

The tiltable racks are so formed that the trays may be placed in the rack from the end running parallel with the axis of rotation. This does not require that the trays be fastened in the racks before the racks are turned. If the trays are slipped into the guides of the racks, the trays cannot fall out when tilting.

The advantages of my invention lie in the fact that I secure a gentle circular movement of the air which brings into motion the entire volume of air contained in the incubator. This air is heated for each section, each section having its own separate heating unit and automatic regulator. The construction is very simple, the regulation of the heat and moisture is relatively easy and the removal or replacement of the racks is easy.

Obviously many minor changes might be made without departing from the spirit of the invention, as defined in the appended claims.

5 I claim:—

1. An incubator of the character described having at the rear lower portion thereof a longitudinally extending fan shaft extending the whole length of the incubator, fan blades mounted upon said shaft, and a plurality of racks disposed above the fan, each of said racks being mounted on an axle extending from front to rear of the incubator, whereby said racks may be tilted in the longitudinal plane of the incubator, each rack having means extending parallel to the axis of the rack for supporting a plurality of trays therein, each rack being independently tiltable with relation to any other rack.

2. An incubator having a plurality of racks mounted therein for tilting movement in a longitudinal plane of said incubator, each rack having means for holding a plurality of trays, one end of the incubator being formed to provide a hatching section having horizontal racks to receive egg trays, means associated with each incubator rack and with the hatching rack to heat the air immediately adjacent the racks, and means extending longitudinally of the incubator rearward of and beneath said racks whereby the air within the incubator may be caused to circulate from the rear to the front of the rack.

In testimony whereof I affix my signature.

JOHN O. GROSS.
